Fig. 5

FIGURE 1 is a front elevational view of the canned oil dispenser showing my new design, equipped with a canopy and with the door in its open, stored position.

FIGURE 2 is a front elevation of the design of FIGURE 1 but showing the door in its closed position.

FIGURE 3 is an end elevation as viewed from either side of either of the FIGURES 1 and 2.

FIGURE 4 is a front elevational view of a modified form of the canned oil dispenser showing my new design, without the canopy and with the door in its open, stored position.

FIGURE 5 is a front elevation of the design of FIGURE 4 but showing the door in its closed position.

FIGURE 6 is an end elevation as viewed from either side of either of the FIGURES 4 and 5.

The sides opposite to those shown in the various figures are substantially the same as those shown in the respective figures.

This application is a continuation application of my copending applications Serial Numbers D. 67,218 and D. 67,219 both of which were filed on October 23, 1961 and which have become abandoned since the filing of this application.

I claim:

The ornamental design for a canned oil dispenser, as shown and described.
